UNITED STATES PATENT OFFICE

JOHN HARLEY, OF GLASGOW, SCOTLAND, ASSIGNOR TO BROWN & SHARPE MFG. CO., OF PROVIDENCE, RHODE ISLAND

INDEX CENTER

Application filed September 22, 1931. Serial No. 564,406.

This invention relates to index centers, and more particularly relates to the indexing discs, the primary object of the invention being to enable the work to be turned throughout a greater range without changing the disc.

Index discs of common usage are nominally used for dividing a circle into a definite number of equal parts (not degrees and minutes) in the milling of teeth and gear wheels, and hexagonal and square milling of shafts.

The method usually adopted for angular indexing is as follows:

15 Divide 540 by the total number of minutes to be indexed. If the quotient is approximately equal to the number of holes in any index circle available the angular movement is obtained by moving the crank one hole in 20 this index circle; but if the quotient is not approximately equal, multiply it by any trial number which will give a product equal to the number of holes in an available index circle and move the index crank as many 25 holes as are indicated by the trial number. If the quotient of 540 divided by the total number of minutes is greater than the number of holes in any of the index circles, it is not possible to obtain the required movement 30 for the angle by simple indexing.

This shows that, only some of the angles in degrees and minutes, can be obtained accurately by simple indexing, and compound indexing, which would be more accurate, involves greater calculations on the part of the workman, and leads to errors.

The above method also shows that for different angles, different discs are often required, and it is only possible to turn the 40 work through this angle and back to zero; therefore, it is not possible to turn the work accurately through a succession of angles in degrees and minutes in many cases. If a change of disc is necessary it would be impossible to place the second disc in the same 45 position as the first one, due to the index crank not being opposite a hole. The present invention therefore aims to provide a disk which overcomes the objection supra and in 50 which when milling at an off angle is re-

quired the templets which are made to a protractor and which do not give the same degree of accuracy and are more costly, are dispensed with.

In the drawings:—

55 Figure 1 is a vertical sectional view of an indexing center having the present invention applied thereto;

Figure 2 is a plan view of one form of indexing disc;

Figure 3 is an edge view thereof;

Figure 4 is a plan view of the reverse side of Figure 2;

Figure 5 is a plan view of the modified form of the invention wherein the holes are 60 drilled completely through;

Figure 6 is an enlarged section on the line 6—6 of Figure 2 and

Figure 7 is a similar section on the line 7—7 of Figure 2.

70 Figure 1 of the drawings illustrates a milling machine having a worm shaft 1 operated by an arm 2 and a handle 3, the handle having the usual spring pressed releasable pin 4 which engages in a selected 75 one of the perforations of the indexing disc 5. The worm 6 of the shaft 1 meshes with a worm gear having ratio of 40 to 1 to the gear 7 which in turn operates the spindle 8 upon which the work is supported. A 80 releasable latch or zero pin 9 engages in perforations upon the rear of the disc 5 and at the bottom of the latter. The invention resides particularly in the location of the openings for receiving the pin 9.

85 In Figure 2 it will be seen that there are six series of circumferential openings 10, 11, 12, 13, 14, and 15; the series 10 being composed of 20 holes, the series 11 composed of 19 holes, the series 12 composed of 18 holes, the series 13 composed of 17 holes, the series 14 composed of 16 holes, and the series 15 composed of 15 holes, the number of holes being indicated as shown at 16, all of the holes in question appearing on the one side 90 face of the disc. Referring to Figure 5 it will be seen that the standard series of holes 19 are 18 in number. The standard series of holes must be 9 or any multiple of 9, by reason of the action of the worm 6 on the 95 100

gear 7 operating the shaft 8 which carries the work, the worm being geared to the shaft as of one (1) to forty (40) as shown in Figure 1.

- 5 Referring to Figures 4 and 6 it will be seen that the disc is provided with holes 17, certain of which extend but partly through the disc thereby to provide cranking or movement of the disc in a clockwise movement. In Figure 3 it will be noted that the peripheral edge of the plate is marked to identify the 29 holes which constitute the circular series of holes 17 as shown at 18.
- 10 The above form of the invention is particularly for use with angular indexing and it will be noted that the 20 holes in the outer circle or series 10 of the standard 20 hole disc extend but slightly more than half way through the disc and that the differential 15 index holes are drilled from the opposite side of the disc, that is on the side next the zero pin in the dividing head. Referring to Figure 5 of the drawings it will be noted that the disc 1a is provided with a series of 20 holes 19 which are marked from 1 to 18 and which are the standard holes, while a second series of holes 20 constituting a total of 29 are off-set circumferentially from the standard 18 holes by an amount which is 25 equivalent to 1, 2, 3, etc., minutes on the work. The disc is marked on both sides to accommodate cranking in either a clockwise or counter clockwise direction, and the indexing for degrees and half degrees is the 30 same as the present on all dividing heads, the addition of minutes from 1 to 29 being the only difference.
- 35 In use of the invention for cranking in a clockwise direction and referring to Figure 5:

Example 1

It is desired to rotate the work through and $3^{\circ} 18$ minutes.

- 40 See that zero pin and crank pin are inserted in their respective zero holes.

45 Withdraw crank pin and swing crank through 3° i.e. $6/18$ and insert crank pin.

- 50 Swing register arm 21 around against crank pin to approximately locate its position.

Withdraw crank pin and zero pin.

Turn index plate around and insert zero pin in 18 minute hole.

- 55 Swing crank in a clockwise direction until crank pin enters the first hole. This gives the desired angle to the work.

Example 2

- 60 It is desired to rotate the work through a further angle of say 3 degrees, 14 minutes, starting where we left off in the first example.

65 Swing crank through 3 degrees from present position.

55 Swing register arm against crank pin.

Withdraw crank pin and zero pin.

(It is now necessary to add the minutes only, i. e. $13' + 14' = 27'$.)

Turn index plate and insert zero pin in 27 minute hole.

Again turn crank until crank pin enters the first hole in a clockwise direction. The work has now been rotated through a total angle of 6 degrees 27 minutes:

(If when rotating the work through several angles, the addition of the last number of minutes comes to 60 or 30, the zero pin should be inserted in the zero hole, and the crank turned to the first hole in a clockwise direction as before.)

Example 3

The angle required is say 1 degree 49 minutes.

Swing crank through $1\frac{1}{2}$ degrees and add 19 minutes as before.

It will be seen that in each form of the invention there occurs a standard circumferential series of 18 holes and a second series of holes off-set circumferentially from the standard series by an amount which is equivalent to the number of minutes on the work. In the form of the invention shown in Figures 2, 3, and 4, the only difference over the form shown in Figure 5, is that the former is for use with angular indexing.

Having thus described my invention what I claim as new and desire to secure by Letters Patent is:

1. An index centering disc, comprising an index plate provided with a standard series of holes marked from 1 to 18 and a second circular series of holes constituting a total of 29 which are off-set circumferentially from the first named series by an amount which is equivalent to the number of minutes on the work, the plate having markings on both sides to provide for cranking in a clockwise or counter clockwise movement or direction, the periphery of the plate having appropriately designated indicia thereon and spaced to correspond with the series of 29 holes to indicate the number of minutes on the work.

2. An index centering disc, comprising an index plate provided with a standard series of holes marked from 1 to 18 and a second circular series of holes constituting a total of 29 which are off-set circumferentially from the first named series by an amount which is equivalent to the number of minutes on the work, the periphery of the plate having appropriately designated indicia thereon and spaced to correspond with the series of 29 holes to indicate the number of minutes on the work.

3. An index centering disc, comprising an index plate provided with a standard series of spaced holes, and a second circular series of spaced holes which latter are offset cir-

cumferentially from the first named series by an amount which is equivalent to the number of minutes on the work, said last named series of holes extending into the 5 plate a distance less than one-half the thickness of the latter, and said plate having markings on both sides to provide for cranking in a clockwise or counter clockwise direction.

10 4. An index centering disc, comprising an index plate provided with a standard series of spaced holes, and a second circular series of spaced holes which are offset circumferentially from the first named series by an 15 amount which is equivalent to the number of minutes on the work, said last named series of holes extending into the plate a distance less than one-half the thickness of the latter, and the periphery of said plate having 20 appropriately designated indicia thereon to correspond to the last named series of holes whereby to indicate the minutes on the work.

In testimony whereof I have signed my 25 name to this specification.

JOHN HARLEY.
